SLIDING WINDOW

Karl Braun, Augsburg, Germany

Application March 20, 1933, Serial No. 661,825
In Germany March 23, 1932

6 Claims. (Cl. 20—42)

The invention relates to a sliding window and particularly to a guide and stop device for the upper sash of a two-part sliding or drop window.

The upper sash of windows of the above 5 named kind is usually adapted to slide between guide flanges, which are fixed to the window posts and extend substantially over the upper part of the window opening, and the lower end of the window is equipped with laterally projecting pins sliding in vertical guides in the window posts. When the upper sash of a window of this kind is lowered the upper end of same will finally slide out of the guide flanges and, when in this position, the window tends to 10 drop inward. This is of course a serious drawback, since in such case the person handling the window may be injured or the window itself may be damaged. The main purpose of the invention is to provide means for preventing inadvertent and undesired tiltings of the upper sash when this is lowered into its lowermost position.

In accordance with the invention, upwardly opening stop notches for the guide pins of the upper window are arranged at the lower end of 15 said guide channels in such a height, that, when the upper window is lowered, the guide pins and consequently the sash are stopped before the upper end of same gets out of engagement with the guide flanges.

20 The invention also comprises means which will allow a limited and controlled inward tilting of the upper sash when in its lowermost position. This means consists in substantially vertical guide slots, which communicate with the upwardly opening stop notches and are arranged in staggered relation to the same. The lower ends of these slots communicate with downwardly opening stop notches, which preferably are arranged substantially vertically below the 25 said upwardly opening stop notches. By an auxiliary manipulation the guide pin of the sash may be lowered from the top to the bottom notch the upper end of the sash meanwhile sliding out of engagement with the guide flanges and tilting inward, whereby the guide pins of the sash are automatically forced into the lower downwardly 30 opening stop notches and the sash is held in a position in which the outer side of the same 35 without difficulty may be cleaned.

40 The said communicating stop notches and guide slots or grooves may be formed in the window posts proper but are preferably formed in plate-shaped bodies of metal or other suitable 45 material which are fixed to the window posts 50

at the lower ends of the guide channels for the guide pins.

A constructional form of the invention is illustrated by way of example in the accompanying drawing:

Fig. 1 is a front elevation of a two-part sliding or drop window according to the invention.

Fig. 2 is a transverse vertical section through the same window.

Fig. 3 shows a detail.

In the drawing 1 denotes the window posts of a two-part sliding or drop window comprising an upper window 2 and a lower window 3. The lower end of the upper window 2 is equipped with laterally projecting guide pins 4 adapted

to slide in guide channels 5 in the window posts. 6 denotes vertical guide flanges which extend substantially over the upper half part of the window opening and between which the upper window slides with a suitable play.

At the lower ends of each of the guide channels 5 a plate-shaped body 7 is fixed in which stop notches and guide slots are formed. The upwardly opening stop notch 8 (Figs. 2 and 3) forms in a way an extension of the guide channel 5. In staggered relation to the notch 8 a vertical slot 9 is formed the upper end of which

communicates with the notch 8 and the lower end of which communicates with a downwardly opening stop notch 10 arranged below the

notch 8.

When the upper window 2 is lowered in the normal way the guide pins 4 will finally abut against the bottom of the notches 8, whereby a further lowering of the window is prevented.

The notches are as mentioned arranged on such a level that the downward movement of the upper window 2 is stopped before the upper end of the same gets out of engagement with the guide flanges 6.

If it is desired to inspect or clean the outer side of the window 2 the same is lowered as usual and during the last stage of this movement the lower end of the window is pulled inward. The effect of this action is,

that the pins 4 will not be caught by the notches 8 but will enter the slots 9. These slots are of

such a length, that the pins 4 will reach the bottom of the slots when the upper end of the window slides out of engagement with the guide flanges 6.

At this moment the upper portion of the window will tilt inward whereby the pins 4 are automatically forced into the notches 10,

which will hold the window securely in the position indicated in dotted lines in Fig. 2.

The described arrangements may of course be

varied in different ways without departing from the scope of the invention as set forth in the appended claims.

I claim:

5. 1. A guide and stop device for the upper sash of a two-part sliding window comprising lateral guide flanges for said upper sash extending substantially over only the upper half part of the window frame, laterally projecting guide members on the upper sash adapted to slide in guide channels in said frame and stop means cooperating with each guide member of the upper sash and having two vertically spaced rest notches, one for supporting the upper sash in fully lowered position clear of said guide flange whereby the sash can pivot about said rest, and the other rest notch for supporting the upper sash in nearly lowered position with said guide flange preventing its pivotal movement, said stop means having also a groove connecting the rest notches in such a manner that an auxiliary manipulation of the sash is necessary to shift the guide member from one rest notch to the other. 10 15 20 25 30 35 40 45 50 55 60 65 70 75 80 85 90 95 100 105 110 115 120 125 130 135 140 145 150
2. A guide and stop device for the upper sash of a two-part sliding window comprising lateral guide flanges for said upper sash extending substantially over only the upper half part of the window frame, laterally projecting guide members on the upper sash adapted to slide in guide channels in said frame, stop means cooperating with each guide member of the upper sash and having an upper rest notch aligned with the path of the guide member for supporting the sash in nearly lowered position still guided by the guide flanges, a lower rest notch aligned with the upper rest notch for supporting the sash in fully lowered position clear of the guide flanges, and a groove laterally offset from said notches and connecting the same, the upper notch having a lip between it and the groove over which the guide member has to be lifted in passing from the upper to the lower notch. 3. A guide and stop device for the upper sash of a two-part sliding window comprising lateral guide flanges for said upper sash extending substantially over only the upper half part of the window frame, laterally projecting guide members arranged at the lower end of said sash, guide channels in said frame adapted to receive the guide members, and plates arranged at the lower end of said guide channels and having upwardly opening stop notches arranged at the lower end of said guide channels and adapted, when the upper sash is lowered, to stop the downward movement of this sash whilst the upper end of same is still in engagement with the guide flanges. 4. A guide and stop device for the upper sash

of a two-part sliding window comprising lateral guide flanges extending substantially over only the upper half part of the window frame, laterally projecting guide members arranged at the lower end of said sash, guide channels in said frame adapted to receive the guide members, plates arranged at the lower end of said guide channels and having upwardly opening stop notches arranged at the lower end of said guide channels and adapted, when the upper sash is lowered, to stop the downward movement of this sash whilst the upper end of same is still in engagement with the guide flanges, substantially vertical guide slots arranged in said plates in staggered relation to said stop notches, communicating with same and with said guide channels and allowing said upper sash to be lowered until the upper end of same slides out of the guide flanges, and downwardly opening stop notches in said plates communicating with said guide slots and adapted to receive and hold said guide members when the upper end of the sash tilts inward on leaving the guide flanges.

5. A sliding window construction comprising in combination a lower sash, an upper sash, window posts, laterally projecting guide members attached near the lower end of said upper sash, guide channels for said guide members in said posts, guide flanges on said posts extending substantially over only the upper half part of the posts, and stop notches arranged at the lower end of said guide channels and adapted, when the upper sash is lowered, to stop the downward movement of this sash whilst the upper end of same is still in engagement with the guide flanges.

6. A sliding window construction comprising in combination a lower sash, an upper sash, window posts, laterally projecting guide members attached near the lower end of said upper sash, guide channels for said guide members in said posts, guide flanges on said posts extending substantially over only the upper half part of the posts, upwardly opening stop notches arranged at the lower end of said guide channels and adapted, when the upper sash is lowered, to stop the downward movement of this sash whilst the upper end of same is still in engagement with the guide flanges, guide slots communicating with said guide channels and said stop notches and allowing said upper sash to be lowered until the upper end of same slides out of the guide flanges, and downwardly opening stop notches communicating with said guide slots and adapted to receive and hold said guide members when the upper end of the sash tilts inward on leaving the guide flanges.
